UNITED STATES PATENT OFFICE.

JOHN H. WHITAKER, OF DAVENPORT, IOWA.

IMPROVEMENT IN PICKET-POINTING MACHINES.

Specification forming part of Letters Patent No. **175,540**, dated March 28, 1876; application filed July 15, 1875,

To all whom it may concern:

Be it known that I, JOHN H. WHITAKER, of Davenport, in the county of Scott and State of Iowa, have invented certain Improvements in Picket-Pointing Machines, of which the following is a specification:

My invention relates to a revolving knife-head attached to an arbor. To this head are secured two or more bent or straight knives, made in just the form to suit the mold desired, and they are so sharpened that when they strike the wood they give a shearing cut, thus leaving the picket-head clean and smooth, this being one of the great advantages gained.

Figure 1 is an isometrical view embodying my invention. Fig. 2 is a model size of the knife-head, showing knives planted and bolted on. Fig. 3 is a section of the knife-head, also showing knives bolted on knife-head. Fig. 4 shows knife sharpened, and a portion of knife-head with a washer between knife and knife-head.

a is the frame of the machine. *b* is the knife-head. *c* is the arbor. *d* are the knives. *e*, the bolts securing the knives to knife-head,

leaving a space for shavings to pass through between knives and knife-head. *g* is the picket bed or table. *h* is the picket, the foot being placed on a rest at *i*. The top is swung against the knives at *j*. *k* shows a curve in the knife made for the purpose of giving a shearing cut. *l*, in Fig. 3, shows a curve in the knife, which is supposed to be made to the form of mold or design required. When the picket head or top is to be formed the foot of the picket is placed against the rest *i*, and the top swung against the knives at *j*, taken up and turned over same operation repeated, and the picket is complete. The machine can also be used for any purpose where cutting across the grain is required.

I claim—

The combination of the knife *d*, revolving knife-head *b* and washers *f*, or their equivalent, as and for the purposes hereinbefore set forth.

JOHN H. WHITAKER.
